UNITED STATES PATENT OFFICE.

AUGUST F. FLECK, OF WEST ENGLEWOOD, NEW JERSEY, ASSIGNOR TO WASHBURN & GRANGER, INC., OF NEW YORK, N. Y., A CORPORATION OF NEW YORK.

DOOR AND HOIST MECHANISM FOR HATCHWAYS.

Application filed November 13, 1923. Serial No. 674,541.

This invention relates to hatchway doors and hoists and control and operating means therefor.

The invention has been particularly 5 worked out in connection with sidewalk hatchways or hoistways in which doors are provided for closing the opening and operating means is mounted in the hatchway for raising the doors and the hoist. With this 10 type of structure it is highly desirable and is often required by the authorities that an alarm be sounded when the doors are opened to warn pedestrians and to prevent their being injured.

15 One of the objects of the invention is to provide door opening means and locking and control means therefor so constructed and arranged that an alarm will be sounded before the doors commence to open and 20 during their opening movement and also during the closing movement.

Another object of the invention is to provide means for securely retaining the doors and the guards carried thereby in position 25 after the doors have been opened.

Another object of the invention is to provide hoisting means so constructed and arranged that the same hoisting means will operate successively to open the doors and 30 raise the hoist.

Further objects of the invention will appear from the following specification taken in connection with the drawings, which form a part of this application, and in which

35 Fig. 1 is a sectional elevation of a hatchway showing the doors in open position and the hoist in its lower position.

Fig. 2 is a sectional elevation similar to Fig. 1, but showing the hoist in elevated position, this view also illustrating the doors in dotted lines in closed position.

40 Fig. 3 is a perspective view showing the construction of the doors and the guards carried thereby.

45 Fig. 4 is a sectional elevation on an enlarged scale taken substantially on line 4—4 of Fig. 2.

Fig. 5 is an enlarged sectional elevation 50 showing the lock pin for the mast of the hoist.

Fig. 6 is a view similar to Fig. 5, but showing a modified construction of releasing means for the lock pin.

55 Fig. 7 is an enlarged elevational view partly in section showing the reverse side

of the panel or casing on which are mounted the sheaves around which the hoisting cable passes and also showing the locking means for the doors and the alarm switch, and

Fig. 8 is a sectional elevation taken substantially on line 8—8 of Fig. 7.

The invention briefly described consists of hatchway doors movable to open and closed position, means for opening the doors, means for locking the doors in closed position and 65 alarm control means operated by the retraction of the locking means whereby an alarm is given as soon as the doors are released and before they start to open. The operative mechanism for opening the doors is also 70 constructed and arranged to raise the hoisting mechanism or mast carrying this mechanism and operates first to raise the doors and subsequently to raise the mast. In the reverse direction, the mast is lowered first 75 and thereafter the doors are closed. Further details of the invention will appear from the following description.

In the embodiment of the invention illustrated, there is shown a hatchway 10 having channel irons 11 mounted at the upper end thereof and doors 12 and 13 pivoted at 14 in the channel irons 11. Referring particularly to Fig. 3, it will be seen that the door 13 has a guard 15 rigidly secured thereto at 16 and braced at 17. The door 12 has hinged thereto at 18 a guard 19 which as shown at 20 overlaps the rigid guard 15. The guard 19 is normally maintained in engagement with the guard 15 as shown in 85 full lines in Fig. 3 by springs 21.

A channel iron 25 is secured to one wall of the hatchway and a mast 26 for the hoist is mounted in the channel iron in guideways formed by guide strips 27. An angle iron 95 28 is bolted to one edge of the channel iron as shown at 29 and there is secured to this angle iron a panel or plate 30 having along one edge a recess 31 for receiving the outer edge of one side of the channel iron. A 100 bracket 32 at the lower end of the plate 30 secures the plate to the wall of the hatchway opening.

Three sheaves 35, 36 and 37 are mounted on the plate 30 on stationary pivots, these 105 sheaves being partly covered by guard casings 38. A fourth sheave 40 is also carried by the plate 30 but is vertically movable with respect thereto. The sheave 40 is mounted on a pin 41 secured in a casing 42 110

and the casing 42 is slidably mounted in a slot 43 formed in the plate 30. As shown in Figs. 7 and 8, the pin 41 extends through the slot and through an elongated bar 44 which 5 is secured to the casing 42 by means of bolts 45. From the showing particularly in Fig. 8, it will be seen that an extension 46 of the casing 42 extends through the slot 43 and that an extension 47 at the lower end of the 10 casing 42 also extends through the slot and is secured to the bar by a bolt 48.

The pin 41 also has mounted thereon a sleeve 49 on which are mounted links 50 and 51 which are connected at their upper ends 15 respectively to the doors 12 and 13.

When the doors are in their closed position as shown in dotted lines in Fig. 2, the sheave 40, casing 42 and parts carried thereby are disposed in the lower portion of the slot 43. 20 The upward movement of the casing 42 and sheave 40 is limited by an adjustable stop in the form of a bolt 52 which is threaded into the upper end of the casing 42 and is adapted to engage the lower end 53 of the 25 sheave cover 38 of the sheave 35. A lock nut 54 is mounted on the bolt 52 for locking this stop bolt in adjusted position.

A lock pin 60 is slidably mounted in a bracket 61 secured to the back face of the 30 plate 30 (looking at Fig. 2) and a spring 62 normally urges this lock pin into locking position. The pin 60 is adapted to engage or seat in a recess 63 formed in one edge of the bar 44 as shown in dotted lines in Fig. 35 2. The lock pin has a cross pin 64 extending through the shank 65 thereof and this cross pin is adapted to be engaged by a bifurcated wedge 66 slidably mounted on the bracket 61 and normally held in retracted position by a spring 67. A chain 68 is secured to the lower end of the wedge for facilitating the manipulation thereof.

In addition to the function of locking the doors in closed position, the stop pin 45 60 and shank 65 thereof are also adapted to control an alarm circuit since a switch 70 which is included in the circuit of an alarm device, such as a bell 71 shown in Fig. 1, is disposed in alignment with the shank 65. 50 When the lock pin is retracted from its locking position, the shank 65 engages the switch 70 and closes the alarm circuit thereby sounding the alarm 71. Attention is called to the fact that the alarm is sounded 55 before the doors commence to open.

In order to open the doors, the sheaves 40, casing 42 and parts carried thereby are raised from the dotted line position shown in Fig. 2 to the full line position by means hereinafter described. When the doors are unlocked by retracting the lock pin 60 and the raising mechanism is operated, the locking pin 60 will ride on the edge 72 of the bar 44 until the doors reach their open position whereupon the lock pin 60 will be

returned to its initial or locking position as the door has been moved upwardly to a sufficient extent to clear this locking pin. When the locking pin is so moved, the alarm switch 70 will be automatically opened by the 70 springs 73.

The door opening mechanism comprises in this instance a cable 80 having one end secured to a winch 81 mounted on the channel iron 25. This cable passes upwardly over 75 the sheave 37 under the sheave 40 over the sheaves 35 and 36 and downwardly from the sheave 36 to the lower end of the mast where it is secured to the mast as shown at 82.

Means is provided for automatically locking the mast in its raised position. This means comprises a mast lock pin 85 slidably mounted in a bracket 86 secured by bolts 87 between the two angle irons 85 which form the mast 26. The mast lock pin, as shown in Fig. 5, comprises a plunger 88 having an annular groove 89 adjacent one end thereof and an annular shoulder 90. A spring 91 is seated in a recess 92 formed in the bracket 86 and engages the shoulder 90. The plunger 88 is hollow and has slidably mounted therein a pin 93 having a head 94 and a shank 95. A spring 96 is mounted in the hollow plunger and engages the head 94 of the pin 93. A cross pin 97 extends through the shank 95 and when the mast is locked, the pin 97 seats against the end of the hollow plunger 88.

An opening 98 is formed in the channel iron 25 and is so located that when the mast is in its raised position, the mast lock pin 85 will be disposed opposite this opening. When the mast is raised, the end of the plunger 88 will snap through the opening 98 under the pressure of the spring 91. The mast 26 and hoisting means carried thereby will thereupon be lowered slightly until the lower edge of the opening 98 is seated in the lower portion of the groove 89 of the plunger. In order to release the mast when the hoist is to be lowered, the lock pin 93 is retracted and the cross pin 97 is moved to the dotted line position shown in Fig. 5. This will place the spring 96 under tension sufficient to overcome the action of the spring 91 and when the operator rotates the winch 81 sufficiently to lift the mast slightly, the lock pin 85 will snap out of the opening 98 and the mast will be released.

In order to provide for releasing the mast when the mast has been raised to a position out of reach of the operator, there is shown in Fig. 6 a slideable wedge 100 normally retracted by a spring 101 and adapted to engage the cross pin 97. A chain 102 is secured to the wedge 100 and when the chain is pulled, the wedge will engage the cross pin and retract it whereupon the lock will 125 130

be released in the manner already described.

In order to secure the doors in their open position, a bar 105 is pivoted at 106 to a bracket 107 carried by the mast 26. This bar normally engages a guide 108 but when the mast is raised, the bar swings downwardly by gravity to the position shown in Fig. 2 in which position it engages the door 13.

10 Any suitable hoisting means may be carried by the mast 26 and in the embodiment of the invention shown a gear operated winch 110 is mounted on the upper end of the mast.

15 The construction above described operates as follows. Assuming that the doors are in closed position as shown in dotted lines in Fig. 2, the operator will first manually retract the door lock pin 60 by pulling downwardly on the wedge 66. This retraction of the locking pin also closes the alarm switch 70 and causes the alarm to sound before the doors commence to open. When the door lock pin has been retracted, the 20 winch 81 is operated and winds the cable 80. This winding up of the cable will first shorten the loop which passes around the vertically movable sheave 40 lifting this sheave to the full line position shown in Fig.

25 30 2 from the dotted line position shown therein. As this sheave and the casing 42 and parts carried thereby are lifted, the links 50 and 51 will raise the doors 12 and 13 to open position. During this opening movement, the door lock pin 60 will be main-

35 tained in retracted position by its engagement with the edge 72 of the bar 44 until the pin rides off of the lower end of the bar and is then returned to its normal position by the spring 62. After the doors have 40 been raised to open position, continued operation of the winch and shortening of the cable 80 will lift the mast 26 from the position shown in Fig. 1 to the position

45 shown in Fig. 2. When the mast reaches the upper limit of its movement or its raised position, the mast lock pin 85 will snap into the opening 98 in the channel iron 25 and the mast will be thereby locked in raised 50 position. As the mast is raised, the arm 105 will ride on the guide 108 and will eventually swing down to the position shown in Fig. 2, thereby locking the doors in open position.

To close the doors and lower the mast, the shank of the pin 93 is retracted, placing the spring 96 under tension and the mast is lifted slightly until the head of the plunger 88 recedes from the opening 98 in the channel iron 25. The mast will then 60 move down by gravity as the cable 80 is slackened off by the winch and when the mast has reached its lower position, the sheave 40 and parts connected thereto will move downwardly in the slot 43 of the plate 30, 65 thereby permitting the doors to close.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. In combination, hatchway doors movable to open and close the hatchway, a hoist movable through the hatchway opening and common means operable successively to first open the doors and then raise said hoist.

2. In combination, hatchway doors movable to open and close the hatchway, a hoist movable through the hatchway opening and common means, including a cable and winch, operable successively to first open the doors and then raise said hoist.

3. In combination, hatchway doors movable to open and close the hatchway, a hoist movable through the hatchway opening and common means, including a cable, a vertically movable sheave and means for winding up said cable, operable successively to first open the doors and then raise said hoist.

4. In combination, hatchway doors movable to open and close the hatchway, means for opening said doors including a vertically movable sheave connected to said doors in all positions thereof and means for raising said sheave.

5. In combination, hatchway doors movable to open and close the hatchway, means for opening said doors including a vertically movable sheave connected to said doors in all positions thereof and means, including a cable and winch, for raising said sheave.

6. In combination, hatchway doors movable to open and close the hatchway, means for opening said doors including a vertically movable sheave connected to said doors in all positions thereof, means for raising said sheave, and stop means for limiting the movement of said sheave in both directions.

7. In combination, hatchway doors movable to open and close the hatchway, means for opening said doors including a vertically movable sheave connected to said doors in all positions thereof, means for raising said sheave, and an alarm switch controlled by the movement of said sheave.

8. In combination, hatchway doors movable to open and closed position, a hoist, means for opening said doors and raising said hoist and means carried by the hoist for holding the doors in open position.

9. In combination, hatchway doors movable to open and closed position, a hoist, means for opening said doors and raising

said hoist and means carried by the hoist for holding the doors in open position, said holding means being automatically engageable with the door as the hoist is raised and disengageable with the door as the hoist is lowered.

10. In combination, hatchway doors movable to open and closed position, a hoist, means for opening said doors and raising said hoist and pivoted means carried by the hoist for holding the doors in open position.

11. In combination, hatchway doors movable to open and closed position, a hoist, means for opening said doors and raising said hoist and pivoted means carried by the hoist for holding the doors in open position, said holding means being automatically engageable with the door as the hoist is raised and disengageable with the door as the hoist is lowered.

12. In combination, hatchway doors movable to open and closed position, a hoist, and means for opening said doors and raising said hoist, said means including a movable

sheave connected to the doors, a cable passing beneath said sheave and having one end connected to the hoist and take-up means for said cable.

13. In combination, hatchway doors movable to open and closed position, a hoist movable through the hatchway opening, means for opening the doors and raising said hoist and automatically operable locking means for limiting the upward movement of the hoist.

14. In combination, hatchway doors movable to open and closed position, a hoist movable through the hatchway opening, means for opening the doors and raising said hoist and automatically operable locking means for limiting the upward movement of the hoist, said locking means being so constructed and arranged that the weight of the hoist will aid in retaining the hoist in locked position.

In witness whereof, I have hereunto set my hand this 5th day of November, 1923.

AUGUST F. FLECK.
